LOCOMOTIVE BOILER

Charles Gilbert Hawley, Chicago, Ill., assignor
to Locomotive Firebox Company, Chicago, Ill.,
a corporation of Delaware

Application August 8, 1932. Serial No. 627,907

10 Claims. (Cl. 122—68)

This invention relates to improvements in locomotive boilers and it consists of the matters hereinafter described and more particularly pointed out in the appended claims.

In the operation of a siphon equipped locomotive boiler, severe stresses develop due to the fact that the movement of the crown sheet and siphon while in the same direction, is at different speeds so that their movements are in effect 5 relatively opposite. This relative movement tends to cause a separation of the parts and in some instances, results in a fracture of the metal.

It is apparent that with a considerable vertical length of side sheets for the firebox, compared to the like depth of the siphon, that there 15 will be a greater movement of the crown sheet than of the siphon, because of the greater amount of material therein subjected to expansion stresses. This situation obtains during the 20 heating up of the boiler but is perhaps more pronounced during the cooling off period because there is added to the normal relative difference in movement, a greater relative difference due to the rapid cooling of the siphon, after the 25 dumping of a fire, by virtue of large volume of air flowing into the firebox. This air flow causes a tremendous cooling action in the firebox.

One of the objects of the present invention, therefore, is to improve the structural connection 30 between the crown sheet and associated discharge end of the siphon so as to utilize and increase the flexing possibilities of the crown sheet and siphon sides adjacent the discharge opening of the siphon.

Another object of the invention is to provide a 35 structural connection between the crown sheet and siphon of such design that no substantial amount of the weld extends outwardly beyond the side wall of the siphon to rigidify and minimize the flexible action of the crown sheet.

A further object of the invention is to provide a 40 structural connection of this kind wherein the opening in the crown sheet for the siphon need not be made to an accurate outline but need only approximate the desired outline which may 45 be more or less uneven with a resultant elimination of much hand labor and the reduction of cost of installation.

Again, it is an object of the invention to provide 50 a structural connection of this kind wherein the welding and other necessary installation operations may be carried on entirely from within the firebox.

Still another object of the invention is to provide 55 a construction of this kind which permits

the trimming of the top end of the siphon to fit the different types and sizes of fireboxes so that a lesser number of stock sizes of siphons are required.

The above mentioned objects of the invention, 60 as well as others, together with the many advantages thereof, will more fully appear as I proceed with my specification.

In the drawings:

Figure 1 is a longitudinal vertical sectional view 65 through the firebox end of a locomotive boiler embodying one form of my invention;

Figure 2 is a transverse vertical sectional view through the same as taken on the line 2—2 of Figure 1;

Figure 3 is a horizontal sectional view through 70 the same as taken on the line 3—3 of Figure 1 and discloses the crown sheet in top plan elevation;

Figure 4 is a detail view in top plan elevation 75 of a portion of the crown sheet and more clearly discloses a structure wherein the openings therein for the siphons are of irregular shape or outline;

Figure 5 is a transverse vertical detail sectional view on an enlarged scale as taken on the 80 line 5—5 of Figure 4;

Figure 6 is a longitudinal detail vertical sectional view as taken on the line 6—6 of Figure 5;

Figure 7 is a transverse vertical detail sectional view on an enlarged scale as taken on the 85 line 7—7 of Figure 3;

Figure 8 is a view similar to Figure 7 and illustrates a modified form of connection between the crown sheet and siphon; and

Figure 9 is also a view similar to Figure 7 and illustrates a further modified form of construction.

In general, my invention while addressed to a locomotive boiler, is more particularly concerned 90 with the structural connection between the crown sheet and the elongated hollow wall which forms a siphon. The wall in this instance, is flangeless.

In accordance with the invention, a longitudinal opening, one for each siphon to be installed, 100 is produced in the crown sheet. Preferably this opening should be no larger than the inside of the siphon top but it may be smaller than the same and it also may be somewhat irregular in 105 outline. In locating such an opening, it is preferable that the same be in line with a row of the radial stays, the bottom end of which stays are removed as with a torch when said opening is made. After the opening for each siphon has 110

thus been made, the effective height of the crown sheet and siphon to be applied thereto, is determined and the siphon top is trimmed off, if necessary, to fit the particular firebox.

5 After the siphon top has thus been trimmed and fitted, its top edges are chamfered or bevelled or otherwise formed to leave a rather sharp edge extending toward and for engagement against the underside of the crown sheet about the associated opening.

10 Instead of chamfering or bevelling said edge, I may turn the edge slightly inward. Thereafter with the siphon suitably supported in position with respect to said opening, a weld line is run 15 around the top edge of the siphon to secure the siphon in place, the welding being thus disposed in the plane of the wall of the siphon so that said welding does not act to resist flexing of the crown sheet and so that less of said welding is exposed to the wearing abrasive action of the products of combustion in the firebox.

With a structural connection of this kind, there is no flange on the siphon to stiffen the crown sheet to such an extent that its flexing action 25 is seriously impaired. Thus the crown sheet is capable of such free movement that it does not tend to produce a separating movement between the siphon and the crown sheet. Furthermore it does not so hold either the crown sheet or siphon to such an extent that the production of a fracture is likely.

30 Referring now in detail to that embodiment of the invention, illustrated in Figures 1, 2, 3 and 7, respectively, of the accompanying drawings; 1 indicates the side sheets of a locomotive firebox, that are connected together at the top by an arched crown sheet 2, said sheets extending from the flue sheet 3 to the back sheet 4 and secured thereto in the usual manner. The firebox shown 35 in Figure 1 is of the type including a combustion chamber 5, the bottom 6 of which joins with the front throat sheet 7 of the firebox.

40 8 indicates the top sheet of the boiler shell that merges into the outside sheets 9 to coact with the inside sheets 1 to form the side water legs 10. Associated with the said sheets is the outside back sheet 11 and outside throat sheet 12 to provide the front throat 13 and back water leg 14. The side water legs, back water leg and front throat are all bottomed by a mud ring 15. The crown sheet is stayed from the top sheet by 45 radial stays 16, arranged in longitudinal and transverse rows and the other sheets are suitably stayed together in accordance with standard locomotive boiler practice.

50 17 and 18 indicate respectively, thermic siphons, there being a pair of siphons 17 disposed in the firebox chamber proper and but a single siphon 18 disposed in the combustion chamber. 60 With such an arrangement of siphons, the combustion chamber siphon is arranged in the median lines of the crown sheet while the others are located one on each side of said line as best indicated in Figure 3. Both siphons are alike structurally, and only differ in shape so that a description of one will suffice for both and both siphons may be secured to the crown sheet in the same manner.

70 The siphons each include a flat tubular substantially upright body 19 and a bottom tubular inlet neck 20. The body includes spaced side walls 21—21 and rounded end walls 22 and said walls are staybolted in the customary manner as best shown in Figure 5. These side walls of the body are spaced apart, a distance somewhat

less than the spacing between the rows of radial stays 16 where connected to the crown sheet and which last mentioned spacing is about four inches.

80 In the crown sheet is provided an elongated opening 23 having dimensions no greater than the inside dimensions of the top end of the siphon body and such an opening may be produced along one of the longitudinal lines of stays 16, such stays being burned off at the bottom during the 85 production of such opening as best shown in Figures 5 and 7.

90 After the opening 23 has been formed in the crown sheet to dimensions in accord with the top end of the associated siphon and after the siphon has been trimmed as to height, the 95 trimmed top edge is next prepared for attaching the same to the underside of the crown sheet about said opening. In Figure 7, I have illustrated one manner of so preparing said edges as by chamfering or bevelling the same outward as at 24 to form a sharp edge along and around the inside of the siphon body for engagement or connection with the crown sheet through the medium of the autogenous weld here shown. When 100 the body has thus been fitted, a V-shaped groove is provided in which is disposed a line of welding 25 to operatively secure the siphon body to the crown sheet.

105 Instead of bevelling the top edge of the body described, I may follow the practice shown in Figure 9 wherein the top marginal portions of the body walls are turned inwardly so as to provide bevelled portions 24a. When such an in-turned portion is engaged against the underside 110 of the crown sheet in operative relation, with respect to an opening 23 therein a V-shaped groove results in which a line of welding 25a is laid to secure the siphon in place.

115 In Figures 4, 5 and 6, I have illustrated a crown sheet opening 23a which while generally conforming to the top end of the associated siphon, so far as elongation is concerned, is somewhat irregular in shape about its edges. In Figure 4, this irregularity of shape is emphasized in that 120 one opening is wider at one end than at the other end in the other opening, this arrangement is reversed. Thus as best shown in Figures 5 and 6, the edges of certain parts of said openings are spaced inwardly from the inner surfaces of the 125 walls of the siphons. Such walls are bevelled and welded in place as described in connection with the structure shown in Figure 7.

130 In Figure 8 is illustrated a structure similar to that shown in Figure 7 and differing therefrom only in the fact that the opening 23 instead of being formed to each side of a row of radial stays is formed between two rows of such stays, the bottom ends of which are burned off as with a torch. In such an arrangement a 135 greater distance is provided between the line of welding attachment 25 between the siphon and adjacent rows of stays so that greater flexibility in the crown sheet is thus afforded.

140 With the arrangement described, that portion of the crown sheet adjacent the siphon is more flexible than in a construction including a siphon with a top end flange and therefore, the crown sheet is increased in flexibility to the highest degree it is possible to attain without sacrificing 145 safety.

150 When firing up, the crown sheet because of its area and shape, moves faster than the siphon and flexes to compensate for the relative movement between the two. When the fire is drawn

the siphon cools down faster than the crown sheet and thus we have a second movement which is in the opposite direction and which movement is also relative between the crown sheet and 5 siphon. The movement of the crown sheet to one side and the other of its normal position is best shown in dotted lines in Figures 5, 7 and 8, respectively.

With the arrangement described, the relative 10 movement cannot produce separation between the crown sheet and siphon because of the increased flexibility of the crown sheet and hence cracking or fracture of the metal sheets is prevented.

Specific reference has been made to the thermic 15 siphon, a well-known water circulating and steaming wall, but it should be understood that the invention may be utilized in water circulating and steaming walls of other shapes.

Hence, while in describing my invention, I have 20 referred in detail to the form, arrangement and construction of the various parts, the same is to be considered merely as illustrative so that I do not wish to be limited thereto except as may be necessary by limitation in the appended 25 claims.

I claim as my invention:

1. The method of installing a water circulating and steaming element in the firebox of a locomotive type boiler having a stayed crown sheet, 30 which consists in providing a hollow water circulating and steaming wall having an elongated flangeless top, cutting an opening in the crown sheet smaller than the outside dimension of the top end of the wall, placing the wall with its top end surrounding said opening and substantially 35 in the plane of the underside of the crown sheet, and completing the installation by welding the top end of the wall to the underside of the crown sheet.

2. The method of installing a water circulating and steaming element in the firebox of a locomotive type boiler having a stayed crown sheet, which consists in providing a hollow water circulating and steaming wall, having an elongated 40 flangeless top, cutting an opening in the crown sheet smaller, at least in part, than the outside dimension of the top end of the wall, cutting away end portions of the stays that support the crown sheet portion being removed, placing the 45 wall with its top end surrounding said opening and substantially in the plane of the underside of the crown sheet, and completing the installation by welding the top end of the wall to the underside of the crown sheet.

3. In combination with a firebox, a siphon positioned therein and having an elongated top, 50 said firebox including a crown sheet resting upon edge portions of said siphon top and the crown sheet having a slot of less width than the width

of the siphon top, and a line of welding connecting said siphon edge portions to the crown sheet.

4. In combination with a firebox, a siphon positioned therein and having an elongated top, said firebox including a crown sheet resting upon edge portions of said siphon top and the crown sheet having a slot of less width than the width of the siphon top, and a line of welding arranged in the plane of the intersection of said siphon edge portions and crown sheet respectively, for operatively connecting them together. 80 85

5. In combination with a firebox, a siphon positioned therein and having an elongated top, said firebox including a crown sheet resting upon edge portions of said siphon top and the crown sheet having a slot of less width than the width of the siphon top, said edge portions and crown sheet being formed to coact in providing a substantially V-shaped groove, and a line of welding arranged in said groove for securing said siphon 90 and crown sheet together. 95

6. In combination with a firebox, a thermic siphon therein having an elongated top, said firebox including a crown sheet resting upon the top of the siphon and having a slot of less width 100 and length than said top, the siphon and crown sheet being formed about said slot to coact in providing a V-shaped groove about the edge of said siphon top, and a line of welding in said groove for securing said crown sheet and siphon 105 together.

7. In combination with a firebox, a thermic siphon therein having an elongated top end formed to provide a bevelled edge, said firebox including a crown sheet resting upon said edge 110 and having a slot therein of a less width and length than said top end, and a line of welding connecting said crown sheet and siphon top end together.

8. In combination, a siphon having an elongated top portion and a crown sheet resting upon said top portion, said crown sheet having an elongated slot therein of a less width and length than said siphon top portion and arranged to communicate with the inside of said elongated top 115 portion and welded thereto.

9. In combination, a siphon having an elongated top end defined by a bevelled edge, and a crown sheet resting upon said edge, said crown sheet having an elongated slot therein communicating with the inside of said top end of the siphon, and said top end of the siphon and the crown sheet being welded together. 125

10. In combination with a thermic siphon having a top portion, a crown sheet resting thereon 130 and having a slot of less width and length than said top portion of the siphon and connected thereto by a line of welding.
